INVENTOR

Hugo Tueckmantel
BY Fred C. Fischer

ATTORNEY

UNITED STATES PATENT OFFICE.

HUGO TUECKMANTEL, OF NEWARK, NEW JERSEY, ASSIGNOR TO THE T & L CO. INC., OF NEWARK, NEW JERSEY, A CORPORATION OF NEW JERSEY.

BAG-FRAME LOCK.

Application filed April 5, 1923. Serial No. 629,997.

To all whom it may concern:

Be it known that I, HUGO TUECKMANTEL, a citizen of the United States, residing at Newark, in the county of Essex and State of New Jersey, have invented new and useful Improvements in Bag-Frame Locks, of which the following is a specification.

This invention applies to that class of securing means used to positively hold the opposed sides of a hinged frame in fixed relation when closed.

Locks of such character are commonly employed on travelling bags, valises and like containers in which a key is inserted, pressure applied and the plain unnotched ward of the key used to move a locking member, thus releasing the frame sides, permitting them to open.

It has therefore been one of the objects of the present invention to provide a lock which effectually resists attempts to turn an ordinary key therein, thus providing safety from unauthorized intrusion.

Another aim is to produce a lock the casing of which is shaped and adapted to guide the keeper in entering therein.

A further purpose is in the provision of means for guiding the key straight into its operative position, thus avoiding one of the annoyances of common locks and at the same time lessening the cost of key construction.

Still further objects are, to provide a casing comprised essentially of a single piece of sheet metal, shaped, bent and provided with engaging elements to produce a neat appearing and rigid structure that can be economically manufactured, assembled and applied.

These several objects, aims and purposes are accomplished by the novel and practical construction and arrangement of parts, further on described and shown in the accompanying drawings, constituting a material part of this disclosure, and in which:—

Figure 1 is a perspective view of a bag lock and its keeper as made in conformity with the invention and showing its application.

Figure 2 is a rear side elevational view of the lock, parts being in section to disclose the construction.

Figure 3 is a transverse sectional view taken on line 3—3 of Fig. 2.

Figure 4 is a plan view of the bolt carrying plate and section of the key guide member carried thereby.

55

Figure 5 is a sectional view in perspective illustrating the depressible bolt plate and its associated parts as drawn to an enlarged scale.

Figure 6 is a perspective view of the shift plate controlling the action of the lock.

Figure 7 is a similar view showing a modified form of shift plate.

Figure 8 is another like view illustrating another variation in shift plate construction.

Figure 9 is a side view of the key used in connection with the lock, its stem being partially in section.

Figure 10 is a perspective view showing a portion of a modified form of casing cover plate and barrel integral therewith.

The illustration in Fig. 1 shows fragmentary portions of a conventional bag in which the material of the bag sides is designated by the numerals 15 and 16, the same being sewn or otherwise firmly attached to coverings 17 and 18 enveloping the rigid angular frame members 19 and 20, the latter of which exceeds the cross sectional dimensions of the former and is arranged in overlying relation therewith when the frame sides are closed upon their hinges.

Rigidly fixed to the frame side 19, to extend horizontally outward from its upper member, are two keeper plates 21 containing openings 22 adapted to enter the lock casing and become engaged by the bolts therein.

This casing is composed of a front plate 23 sheared and bent to produce ends 24 and then turned oppositely outward to form feet 25 having openings 26 for the reception of rivets 27 by which they are rigidly secured to the inner surface of the vertical element 28 of frame member 20.

In a like manner the bottom plate 28 is bent rearwardly from the lower edge of the plate 23 and provided at its ends with clip extensions 29 tightly folded over the ends 24, re-enforcing and holding the same in position.

The plate 23 is extended upward and slightly outward along its entire upper edge

30 and adapted to deflect and guide the keepers 21 into the openings 31 in the casing front.

5 A top plate 32 extends from the back of the deflector 30, coincidentally with the bottom plate 28, level with the upper edges of the feet 25 and has at its ends clips 33 folded over the end walls 24, said walls being formed with similar clips 34 folded over the 10 ends of the top plate, as best seen in Fig. 1.

The top plate 32 is further held to the casing by rods 35 riveted therein near its ends, the opposite ends of the rods being riveted in the bottom plate 28 and pass in 15 parallel relation through the casing.

Held by rivets 36, centrally on the top plate 32, is a flanged barrel 37, which may be rectangular, ovoidal, or flat with rounded ends as shown, and which extends upward 20 through an opening in the horizontal element of the frame side member 20, terminating below an escutcheon plate 38, indicated by broken lines in Fig. 1.

A pair of catch bolts 39, having bevelled 25 faces adapted to engage and be depressed upon contact with the keepers 21, are arranged centrally of the openings 31 and rigidly secured at their bases to a bar composed of plates 40, 41 and 42 rigidly held 30 together and perforated, as at 43, near their ends to slide freely on the rods 35, being held in a normally raised position by coiled compression springs 44 encircling the rods as shown in Figs. 2 and 3.

35 The uppermost plate 40 has a central raised portion 45 in which is a key hole 46. The center plate 41 is straight throughout, may differ in thickness and contains a registering key hole 47, and the lower plate 42 40 is formed with a central lowered portion 48 in which is rigidly fixed a guide post 49, extending axially through the key holes to a point slightly above the raised portion of the upper plate.

45 A sleeve 50 is slidably fitted to the barrel 37 and provided with a closed upper end or escutcheon 51 in which is a key hole 52. At the lower end of the sleeve are integral parallel elements 53 passing through the raised 50 portion 45 of the upper plate and then turned outward to form fastening lugs 54.

Said elements 53 are slotted, as at 55, to receive a pair of opposed feet 56 firmly held to the top of the plate by the lugs 54 and formed with the feet 56 is a shell or inner sleeve 57 having a cover portion 58 containing a key hole 59 having a downwardly flanged edge.

These several key holes are made to accommodate a key 60, shown in detail in Fig. 9, its stem being drilled, as at 61, to receive the guide post 49 and provided with a ward 62 having a slot 63.

It is to be noted that, due to the inner 65 guide 58, in which the key hole is flanged

downwardly, the length of the post 49 is materially less than usual, effecting an economy in its construction.

It is further noted that the width of the ward 62 is substantially equivalent to the 70 space between the upper and lower plate members 40 and 42, and that the position of the slot 63 conforms with the location of the center plate 41, the function of this plate being to prevent the ward from turning if 75 there is no slot in it or if the slot be improperly placed.

The several plates 40, 41 and 42 composing the bar are firmly secured together to act as a unit are collectively formed with 80 a recess 64 in their front edge extending past the raised portion 45 of the upper plate and are further recessed to a similar depth as at 65 on one end.

A stop plate 66 having an extended base 85 is slidably arranged in the casing, closely adjacent the front wall 23, its raised central portion entering the recess 64 and containing a slot 67 adapted to receive the ward 62 by which it is actuated.

90 The movement of the plate longitudinally within the casing is limited and controlled by angular notches 68 and 69 in the plate, these notches being receptive of a detent 70 shaped to suit the notches, offset and carried on a spring arm 71 held by a rivet 72 to the bottom plate 28, this arm also acting as a guide for the plate 66, the opposite end of the arm being further secured by having one of the posts 35 pass through it.

100 The plate 66 is provided at one end with a seat or stop 73 at a lower level than the main central portion of the plate, and at the other end, beyond the notches, is a raised stop 74, its upper surface being in the plane 105 of the stop 73.

This plate is clearly shown in detail in Fig. 6 and as assembled in Fig. 2, in which position the stop seat 73 aligns with the recess 64 and the corresponding stop seat 74 110 with the recess 65 in which condition the plate will permit the vertically slidable members of the lock to be depressed, which movement obviously retracts the bolts 39 from the keepers and allows the bag frame 115 to be opened.

When it is desired to lock the bag, the key is inserted, readily finding its proper position and upon turning the key its ward, if 120 properly slotted to clear the plate 41, will enter the slot 67, shifting the plate 66 and causing the detent 70 to spring up and over into the notch 69.

The plate 66, when shifted as last described, presents its stop seats 73 and 74 below the vertically movable plates avoiding the recesses and positively preventing them from being moved down to free the bolts from their keepers.

125 In place of the separate flanged barrel 37 130

held by riveting or otherwise to the casing top plate 32, said plate may be drawn by press methods to produce an integral barrel 37' shaped as preferred and which is more attractive in appearance besides being less expensive in assembling.

In the modification shown in Figs. 7 and 8, the plate 66 is used with certain modifications which render the intermediate element 41 of the vertically slidable plates unnecessary and it is therefore omitted, the construction in all other respects being in accordance with the foregoing description.

The modification consists in the device shown in Fig. 7, of providing one or more laterally extending lugs 75 on the plate 66, these lugs being raised to intercept and prevent turning of the key except its ward be fitted to avoid the lugs in a manner which is clearly apparent.

In a similar manner the lateral flanges 76, as shown in Fig. 8, accomplish the same purpose and further more tend to stiffen the plate, either type of key obstruction simplifying the lock construction by reducing the number of parts.

Although I have described my improvements with considerable detail and with respect to certain particular forms of my invention, I do not desire to be limited to such details since many changes and modifications may well be made without departing from the spirit and scope of my invention in its broadest aspect.

Having thus described my invention, what I claim as new and desire to secure by Letters Patent, is:—

1. A bag frame lock casing having an apertured front wall adapted to receive a keeper, and an outwardly curved flange on said front wall adapted to guide a keeper into the mentioned aperture.

2. A bag frame lock casing comprising unitary front, end and bottom walls, a top plate, lugs formed with said end walls overlying said top plate, other lugs on said top plate overlying the end walls, other lugs on said bottom wall overlying the end walls, and an extension on said front plate adapted to guide keepers into said casing.

3. A bag frame lock comprising a casing, a barrel extending rigidly thereabove, a horizontal bolt carrying bar spring actuated and guided to move towards and from said barrel, a key hole escutcheon carrying sleeve fixed on said bar slidably in said barrel, a shell fixed on the bar interjacent said sleeve midway in the length thereof, and means in the top of said shell for guiding a key entered through said sleeve.

4. A bag frame lock comprising a casing, a barrel extending rigidly thereabove, a horizontal bolt carrying bar spring actuated and guided to move towards and from said barrel, a key hole escutcheon carrying

sleeve fixed on said bar slidably in said barrel, a shell fixed on the bar interjacent said sleeve at its lower portion, an escutcheon at the end of said shell, and a flaring downwardly extending flange at the edge of the 70 key hole in said escutcheon.

5. A bag frame lock comprising a casing, a barrel extending rigidly thereabove, a horizontal bolt carrying bar spring actuated and guided to move towards and from 75 said barrel, said bar being composed of upper, lower and intermediate plates, there being key holes in the upper and intermediate plate, a sleeve fixed on said bar closed at its top and having a key hole therein, a shell 80 extending fixedly into said sleeve, said shell having a key hole in its closed covered portion, flanges formed to extend downward from the edges of the key hole, and a post fixed in the lower of said plates in register 85 with the key holes.

6. A bag frame lock comprising a casing, a barrel extending upward therefrom, two or more plates united at their ends to form a bar movable in said casing in the plane 90 of said barrel, a covered sleeve having a key entrance fixed to the upper of said plates, means for guiding a key fixed in said sleeve below the entrance thereof, a post fixed in the lower of said plates to pass through a 95 key hole in the upper plate, and means between said plates to prevent an improperly fitted key from turning therein.

7. A bag frame lock comprising a casing, a barrel extending upward therefrom, two 100 or more plates united at their ends to form a bar movable in said casing in the plane of said barrel, a covered sleeve having a key entrance fixed to the upper of said plates, means for guiding a key fixed in said sleeve below the entrance thereof, a shift plate adapted to intercept the movement of said plate bar when in one position and permit its depression when in another position, a 105 key enterable said casing through said sleeve adapted to actuate said shift plate, and means for preventing the rotation of an improper key.

8. A bag frame lock comprising a casing, a barrel extending upward therefrom, two 110 or more plates united at their ends to form a bar movable in said casing in the plane of said barrel and having a space between their center portions, depressible key guiding elements fixed to the upper element of 115 said bar, a key actuated shift plate controlling the movement of said bar, and means disposed in the mentioned space to prevent turning of an improper key.

9. A bag frame lock comprising a casing, a barrel extending rigidly upward therefrom, a sleeve closed at its outer end and having a key hole therethrough, said sleeve being slidably fitted in said barrel, a shell 120 fixed in said sleeve, to extend midway there-

through, said shell having a key hole in its closed upper end, a plurality of plates constituting a bar slideable vertically in said casing, said upper and intermediate plates containing key holes, a post fixed in the lower plate, means for normally maintaining said bar in a raised position, bolts carried by said bar engageable with keepers entering said casing and rigid connections

between the bases of said sleeve and shell 10 and said bar.

This specification signed and witnessed this third day of April, 1923.

HUGO TUECKMANTEL.
